FREDERICK WILLIAM SCARFF, OF NORTH KENSINGTON, LONDON, ENGLAND,
ASSIGNOR TO VICKERS LIMITED, OF WESTMINSTER, LONDON, ENGLAND.

MACHINE-GUN MOUNTING.

1,364,525.

Specification of Letters Patent.

Patented Jan. 4, 1921.

Application filed July 30, 1920. Serial No. 400,154.

To all whom it may concern:

Be it known that I, FREDERICK WILLIAM SCARFF, a subject of the King of Great Britain, residing at 18 St. Charles Square, 5 North Kensington, in the county of London, England, have invented certain new and useful Improvements in and Relating to Machine-Gun Mountings, of which the following is a specification.

10 This invention relates to machine gun mountings more particularly designed for use upon aeroplanes or other vehicles and of the kind comprising an elevating arm or bracket upon which the gun is mounted and 15 which is carried by a horizontally rotatable member.

The invention consists of a mounting of the kind referred to in which a single hand operated control lever is adapted to effect 20 the release of a rotatable ring from a fixed ring or the like and the elevating arm from its retaining device, the release of the aforesaid members being either simultaneously effected or one after the other, preferably 25 the ring before the elevating arm, the latter form of release having the advantage that it is a simple matter for the operator to move the gun and supporting ring into any desired position without the balance of the 30 elevating arm and parts carried thereby being upset, so that the ring when free can be rotated carrying around the elevating arm and gun or guns without the operator having to apply simultaneously some force to 35 maintain the balance. When the ring is in the required horizontal position, the elevating arm can then be unlocked for adjustment in the vertical plane.

The invention further consists in adapting 40 the mounting as above described to take either one or more guns as required.

The invention further consists in a mounting of the kind referred to in which an elastic cord or cords are provided and arranged 45 in such a way that the turning moments in the vertical plane due to the weight of the elevating arm and parts carried thereby and due to the tension in the cord or cords are substantially equal and opposite. 50 In the preferred form the method of arranging the elastic cord or cords provides for adjustment of the turning moment in the vertical plane due to the tension in the elastic cord or cords, so that the necessary adjustment for balancing can be made to al-

low of the elevating arm carrying one or more guns.

The invention further consists in a mounting of the above character in which one or more sets of ball or roller bearings between 60 the rotatable and non-rotatable parts of the mounting is or are provided.

The invention still further consists in the provision of a trunnion device for carrying two guns on a mounting of the above character in which each gun can traverse about a separate pivot, while the guns as a unit can elevate or depress about a common axis, the guns being cross connected by an automatically adjustable linkwork or other device to allow the guns to be parallel in all 65 positions, while having universal movement independent of the mounting.

The invention still further consists of other details and arrangements hereinafter 70 described with reference to the accompanying drawings.

In these drawings Figures 1 and 2 are a part plan, in part section, and part sectional elevation of one form constructed in accordance with the invention and adapted to take either one or two guns. Figs. 3 and 4 are similar views of an alternative construction, one of the principal differences being that in the former case the locking segments for 85 the elevating arm are secured to the rotatable ring and always project above the ring, while in the latter case, the locking segments are secured to the elevating arm and are adapted to turn down below the ring 90 when the elevating arm is in the down position. Fig. 5 is a plan view of a trunnion device adapted to be fitted in a mounting shown in Figs. 1 to 4 for enabling two machine guns to be carried by the elevating 95 arm. Fig. 6 is an elevation of Fig. 5. Fig. 7 is an elevation of a crosshead maintaining two guns in parallelism in all positions. Fig. 8 is a side elevation of Fig. 6. Fig. 9 is a detail view of the operating hand lever fixed on the elevating arm. Fig. 10 is a part sectional elevation of another form of mounting adapted to take two guns. Fig. 11 is a detail view showing the arrangement 100 for fitting one gun in place of the two. Figs. 12, 13 and 14 are views of details, Fig. 12 being shown partly in section. Fig. 15 is an elevation on a smaller scale illustrating another form of mounting. Fig. 16 is a plan view of Fig. 15, and Figs. 17, 18, 110

19 and 20 are detail views drawn to a larger scale.

Referring now to Figs. 1, 2 and 9, the mounting consists of a horizontal fixed ring 1 which is shown to be of channel section and on this ring revolves a second ring 2, also substantially of channel section, flanged rollers 3 being carried by the rotatable ring to run upon the ring 1.

10 The rotatable ring is provided with two brackets 4 carrying cylindrical bearings 5 to which are secured pins 6 on which turn the forked ends of a tubular elevating arm 7 bent to a U shape. This provides for the 15 pivoting of the elevating arm on the rotatable ring.

Two pairs of toothed segments 8 are secured to the rotatable ring, one pair on each side of the center line of the mounting and 20 the members of each pair one on each side of the elevating arm, each pair of toothed segments being engaged by a locking pin 9 carried by the elevating arm and adapted to be moved into or out of engagement with 25 the segments as will be hereinafter described.

The outer end of each segment is provided with a guide 10 to receive an elastic cord 11, this cord passing over two grooved 30 pulleys 12, two on each side of and carried by the elevating arm and the free ends being taken under grooves 13 on the forked ends of the elevating arm and then being secured together underneath a guide plate 35 14 secured to the bracket 4.

Centrally at the head of the elevating arm is secured a bracket 15 Fig. 9 on which is pivoted a hand lever 16 and on which are rotatably mounted two pulleys 17. The inner

40 end of the lever 16 is provided with a grooved boss or pulley 18 and over the pulleys 17 and under the boss or pulley 18 passes a flexible wire or the like 19, this wire being housed within the hollow elevat-

45 ing arm and having its two ends taken to the mechanism operating the locking devices of the ring 2 and the elevating arm 7. Each end of the wire 19 is secured to a screwed rod 20 on which a sleeve 21 and adjusting nuts 20^a are mounted. The rod 20 passes through

50 a lug 22, one part of which is secured to a hollow rod 23 passing into the elevating arm and carrying at its upper end the locking pin 9.

55 The lug 22 is pivotally attached to a bell crank 24, pivoted to the bracket 4, and the toe of the bell crank engages under a spring plunger 25 carrying at its end a locking pin 26 sliding in a guideway in the rotatable 60 ring and adapted to engage in holes 27 in the fixed ring 1. The bell crank is under the action of a spring 28 which normally tends to keep its toe in a down position to cause the locking pin 9 to engage the toothed segments 8. The spring plunger 25 is

mounted in a suitable housing 29 on the bracket 4.

On the hand lever 16 being grasped by the operator to displace it, the tension thereby put on the wire 19 by the displacement of the part 18 on the hand lever, draws the rods 20 within the elevating arm and the lugs 22 turn the bell cranks so that the toes thereof move the plungers 25 inward of the housings 29. The locking pins 9 are removed from the segments and the pins 26 are removed from the holes 27 which they were engaging in the fixed ring.

The rotating ring can now be moved around on the fixed ring to the required position and the arm elevated or depressed as desired and as the hand lever 16 is released the locking parts 9 and 26 will engage their respective parts to lock the elevating arm and rotatable ring.

85 The advantage of employing the spring 28 is that it makes the engaging of the pins 9 always certain, even if the pins 26 are not registering with two holes in the fixed ring, a slight displacement of the rotatable ring 90 causing one or both of the pins 26 to engage in a hole or holes 27 in the fixed ring.

It will be observed that as the elevating arm is turned on the pins 6, the pulleys 12 over which the elastic cords pass swing about the same center as the weight of the gun, so that the distances at which the weight of the elevating arm and gun or guns and the opposing forces due to the tensions in the elastic cords act about the pivots of 100 the elevating arm, vary in constant proportion, so that the elevating arm with the gun or guns carried thereby is counterbalanced in any of its positions.

At the head of the elevating arm a tubular socket 30 is secured in which a single gun may be mounted such as by a pillar 31 adapted to rotate in the socket 30 and having the gun 32 mounted on a horizontal pivot 33, thus providing a universal movement of the gun independently of the movement of the mounting.

When two guns are required to be mounted these are mounted on a trunnion device in a manner hereinafter described.

115 Referring now to Figs. 3 and 4 which show a modified construction to that shown in Figs. 1 and 2, it will be observed that the segments 8^a are carried by the elevating arm so that when the elevating arm is down the 120 segments are housed within the body of the aircraft or vehicle.

Further in this construction a slightly different arrangement for locking the segment is shown. In this case a single segment only is provided on each side of the elevating arm and is provided with perforations 34 into which a pivoted locking arm 35 can engage. This locking arm is mounted on a pivot 35^a carried by the rota-

table ring 2 and is under the action of a spring 36 always tending to cause engagement of the arm with the segment 8^a.

The method of mounting the gun on the 5 elevating arm and the arrangement of the hand control lever 16 is the same as that previously described, and the same parts are referred to by the same numerals.

The screwed rod 20 connected to the flexible wire 19 passing through the elevating arm 7, has connected to it a bell crank 24^a, the toe of which engages a spring plunger 25 with a locking pin 26 similar to that hereinbefore described. Pivoted to the bell 10 crank 24^a is a lug 37 engaging or secured to a rod 38, having at its outer end the aforesaid locking arm 35.

In this construction, only one elastic cord 11 is shown for each limb of the elevating 20 arm, the cord being secured to the end of the segment 8^a and passing over a pulley 12^a on the rotatable ring 2 and having the other end secured to this ring as indicated at 39.

Referring now to Figs. 5, 6, 7 and 8 which 25 illustrate a device for use with a mounting as shown in Figs. 1-4 provided with a single gun socket 30, in order to enable two guns to be carried by such mounting. The device consists of a carrier 40 provided with 30 a pair of lugs 40^a through which pass U bolts 41 adapted to engage around the elevating arm 7, the bolts passing through wood chocks 41^a bedding between the lugs 40^a and the elevating arm 7. A central bolt 35 42 passes through the socket 30 on the elevating arm, and through a central aperture in the carrier 40, the upper end receiving a nut 43 to secure the carrier on the bolt. The carrier is provided with two vertical arms 44 with half bearings 44^a to receive a cross shaft 45, the bearings being completed by caps 46 which are secured by bolts to the half bearings 44^a. The ends of the cross shaft 45 are provided with forks 40 47 to receive pins 48 on which gun carriers 49 are mounted. These gun carriers are shaped to conform to the type of gun used. Those shown in the drawings are suitable 45 for the Lewis type of gun as stripped for the air, and are shown with vertical tubes 50 to receive a sighting device. These gun carriers *per se* form no part of this invention.

At the rear, the two guns are cross connected by an adjustable rod 51 with the ends pivotally mounted to forks 52, adapted to fix on the usual spade grips or other suitable parts of the gun. The pivots between the forks 52 and the rod 51 are arranged to be detachable to allow of the rod 51 being detached. For this purpose the ends of the rod are slotted as at 53 the lower ends of the slots being enlarged at 53^a to receive enlarged parts of locking pins 54, accidental removal of which is prevented by

springs 55 between thumb presses 55^a and the fork 52.

By operating the thumb press 55^a to force the pin 54 outward the enlarged part of the pin leaves the enlarged part 53^a of the slot 53 so that the end of the rod 51 can be withdrawn through the slot clear of the pin 54.

It will be seen by this construction that the guns can rotate in the vertical plane on the cross shaft 45 while at the same time 75 they can rotate in the horizontal plane about the pivots 48, and by the cross connection of the rod 51 and forks 52, the guns are always parallel in all positions. Also should either of the guns jam by withdrawing the pivot pin 54 adjacent to this gun, the cross rod 51 can be disconnected from this gun so that the jam can be readily cleared and any necessary repairs done without disturbing the operation of the 85 other gun.

Referring now to Figs. 10, 12, 13, 14 which illustrate another construction of mounting arranged to take two guns, the fixed ring 1 is more or less of Z section and 90 is provided with a vertical rib 1^a on the inner diameter of the top flange.

This ring is perforated in the web for lightening in addition to the necessary holes in the upper flange for locking the two rings 95 together.

The rotatable ring 2 is of channel section and is provided with sets of horizontal and vertical rollers 3^a, 3^b shown as of a ball bearing type which respectively run on the rib 100 1^a and on the inner part of the lower flange of the fixed ring 1. To the ring 2 is secured a notched segment 56 the upper end of which is supported by a bracket 57 also secured to the ring.

It will be observed that the segment 56, the bracket 57 and the base flange 58 form a triangular member and if desired these three parts may be made integral and secured to the ring 2 by means of the base flange. 110

The elastic cord 11 has its ends bound together and retained under a projecting part or guide plate 14 formed integral with the base flange 58, the two parts of the cord then passing around upper and lower pairs of 115 pulleys 13 on the member 57, then down through the guide clip 7^a on the elevating arm. The cord exerts an upward pull on the elevating arm sufficient to balance the weight of the arm and guns in any position. 120 To balance for one or two guns, a second guide clip 7^b is provided on the elevating arm and a second hole 57^a in the bracket 57 for a second position of the upper pair of pulleys 13.

It will be seen that the elastic cord thus forms a continuous loop.

The method of assembling the elastic cord is as follows: The cord is passed under the clip 7^a on the elevating arm and the two 130

parts adjusted in length for the clip to be approximately at the center of the length of the cord. The two ends are then taken upward to pass over the pair of pulleys 13 at 5 the upper end of the bracket 57, then downward along the bracket 57 to the lower pair of pulleys 13, thence along the base of the bracket where the ends are bound together in any suitable way and retained under the projection 14 integral with the base flange 58.

The arrangement of operating the locks for the ring and the elevating arm is similar to the arrangement shown in Fig. 9 which has been previously described. The flexible 15 wire 19 passes over a pulley 59 mounted on a bell crank 60 on the elevating arm 7 and then to a tension adjuster 61 which is connected to one end of a bent arm 62, the other end of the arm carrying a locking pin 63 20 adapted to engage the notches of the segment 56. The arm 62 is connected to one end of a spring 64, the other end of which is anchored as at 65 to the elevating arm 7. The bell crank 60 is provided with a toe 66 25 engaging an enlarged hollow head 67 on a locking pin 68, which when registering with a hole in the outer flange of the ring 1, locks the rings 1 and 2 together. This pin is under the action of a weak return spring 69 30 always tending to force the pin 68 into a locking position. The enlarged head 67 fits over a pin 70 on the bracket 57 and about this pin the elevating arm pivots.

The action is as follows: On tension being 35 applied to the wire 19 by the operation of the hand lever 16, the bell cranks 60 are rotated to lift the toes 66 and raise the heads 67 of the pins 68, to disengage the pins from the fixed ring 1, the travel of the pins and the 40 hollow heads being continued until the lower ends of the heads abut against the pins 70, the rings 2 being unlocked from the ring 1 just before or at the instant the outward movement of the heads 67 is arrested. When 45 the movement of the toes 66 of the bell cranks 60 is arrested any further tension on the wire 19 will now cause it to render around the pulleys 59 and so draw the bent arms 62 and the locking pin 63 away from 50 the toothed segments 56, against the action of the spring 64 so that the elevating arm becomes unlocked from the segments 56 and can then be adjusted in position in the vertical plane. On the tension being relieved, 55 the first action is to allow the spring 64 to bring the arms 62 and the pins 63 back again to lock the elevating arm to the segments 56, the next action being for the spring 69 to return the locking pins inward 60 to lock the rings 1 and 2 together.

To the elevating arm 7 is welded a pair of sockets 71 one on each side of the center line of the arm. In each socket is secured a pillar 72 with a threaded extension 73 to receive 65 a nut 74. The pillars 72 carry half bearings

75 for a cross shaft 76 passing between the pillars and provided at each end with a fork 77 to which the gun carrier 78 is pivoted by means of a pin 79, this arrangement being substantially similar to the arrangement of 70 mounting the two guns on the carrier 44 described with reference to Figs. 5, 6 and 8.

For connecting the two guns at the rear to be parallel, while at the same time allowing either gun to be disconnected for clearing 75 jams or making any necessary repairs, a cross connected tubular bar 82 meshes with two oppositely threaded rods 83 each having an eye 84 connected to a fork 85 by a withdrawable spring plunger 86. One end of the 80 plunger is provided with a cap or head 87 between which and an abutment on the fork 85 a spring 88 is provided. The other end of the plunger is reduced to fit through a circular hole formed in the fork 85, one or more 85 recesses or keyways leading from the hole. At right or any other desired angle with respect to the keyways are one or more recesses 89 which normally are engaged by one or more lugs 90 on the end of the plunger. By 90 pressing the plunger outward the lugs 90 are disconnected from the recesses 89, and the plunger can then be rotated to bring the lugs 90 into line with the aforesaid keyways, whereupon the plunger can be withdrawn 95 from the fork, thus allowing one gun to be disconnected from the other. The rear ends of the forks 85 are secured to a suitable part of the rear ends of the guns such as by a bolt and nut arrangement shown. 100

Should only one gun be required on the mounting, the arrangement shown in Fig. 11 is used, in this case the gun carrier being pivoted vertical on a fork 80 which is horizontally pivoted as at 81 to a pillar 72 secured 105 in the socket 71 as hereinbefore described with reference to Fig. 10. Fig. 11 represents the same mounting as shown in Fig. 10, but where only one socket is used in the elevating arm, so that the cross shaft 75 in this 101 case is obviously unnecessary.

Referring now to Figs. 15 to 20, the sections of the inner and outer rings are of somewhat similar form to those shown in Fig. 10, with horizontal and vertical ball 115 bearing rollers.

The elevating arm 7 is pivoted to a triangular frame 91 secured to the rotating ring 2, and the arm carries toothed segments 92 to engage with locks carried by the rotating ring. 120

A hand lever 16 operating the wire 19 arranged as described with reference to Fig. 9 is employed. Each part of the flexible wire 19 passes over a pulley 93 at the extremity of each limb of the elevating arm, thence to a pulley 94 on a bell crank 95 pivoted to the aforesaid triangular frame 91, the end of the wire being secured to an adjustable threaded rod 96 which is con- 125 130

nected by a cross member 97 to a rod 98 under the action of a spring 99.

The toe of each bell crank 95 engages underneath a spring plunger 100 carrying 5 a locking pin 101 passing through a guide-way in the rotatable ring 2 and adapted to engage in one or other of the holes in the fixed ring 1.

The rod 98 is connected to a locking member 102 pivoted as at 103 to the triangular frame 91, the member 102 being adapted to engage with the toothed segment 92.

The operation is as follows: On the hand lever 16 being operated to put tension on 15 the two parts of the flexible wire 19, each bell crank 95 is rotated to withdraw the locking pin 101 from the inner ring. On the movement of the bell crank or the pin 101 being arrested by the casing or other 20 stop device for the spring plunger 100, the flexible wire 19 renders around the pulleys 94 and draws the rod 98 inward against its spring 99. The inward movement of the 25 rod 98 turns the locking member 102 on its pivot 103 to withdraw it from the tooth of the locking segment 92, whereupon the elevating arm can be raised or lowered as desired. On releasing the hand lever 16 the locking member 102 is brought by the action 30 of the spring 99 into engagement with the segment 92, and the spring locking pin 101 is forced outward to lock the horizontal rings together.

The elastic cord 11 counter-balancing the 35 weight of the elevating arm and parts carried thereby is arranged as follows: Each end 11^a is anchored to a cross pin 104 on the triangular frame 91, and the cord passes over a guide 105 on the frame 91, then 40 downward over a pulley 106 on the segment 92, upward over a pulley 107 on the same pin or center 108 about which the elevating arm turns thence to a hook formed on the upper end of the segment 92. The cord is 45 arranged to exert a pull tending to lift the elevating arm and the pulleys 106 can be adjusted in one or other of the holes 109 provided in the radial arm of the segment 92 in order to balance varying weights such 50 as one or two guns on the elevating arm.

The triangular frame is suitably padded on the inner surface to prevent the operator bruising his body when pressing it against the frame to assist when turning the ring.

55 The rear ends of the guns are cross connected in a manner similar to the arrangement described above with reference to Fig. 12, but the arrangement for release shown in Fig. 19 is slightly modified. In this case 60 the fork 85 referred to in description of Fig. 12 is provided with a rod 110 which has an enlargement 110^a adjacent to the fork, and a threaded outer end 110^b to mesh with a threaded handle 111 provided with 65 an extension 111^a. The enlargement 110^a

and extension 111^a fit in recesses 112 in a part 113 secured to the rear end of the gun, this part 113 being slotted between the recesses. On slackening back the handle 111 sufficiently to allow the parts 110^a and 111^a 70 to become clear of the recesses in the part 113, the rod 110 can be swung clear of the part 113 thus disconnecting one gun from the other.

What I claim and desire to secure by Letters Patent of the United States is:—

1. In a machine gun mounting, the combination with a rotatable training member and an elevating member upon which the gun is mounted and which is pivoted to said training member, of locking means for the training member, locking means for the elevating member, a hand operated control device and means whereby the operation of said device causes both of said locking means to be moved to their releasing positions.

2. In a machine gun mounting, the combination with a rotatable training member and an elevating member upon which the gun is mounted and which is pivoted to said training member, of two sets of locking devices one for locking the training member and the other for locking the elevating member, a single hand operated control member and means whereby the operation of the last mentioned member causes both sets of locking devices to be moved to their releasing positions.

3. In a machine gun mounting, the combination with a rotatable training member and an elevating member upon which the gun is mounted and which is pivoted to said training member, of two sets of locking devices one for locking the training member and the other for locking the elevating member, a single hand operated control member and means whereby the operation of the last mentioned member causes both sets of locking devices to be moved 100 simultaneously to their releasing positions.

4. In a machine gun mounting, the combination with a rotatable training member and an elevating member upon which the gun is mounted and which is pivoted to 105 said training member, of two sets of locking devices one for locking the training member and the other for locking the elevating member, a single hand operated control member and means whereby the operation of the last mentioned member causes 110 both sets of locking devices to be moved simultaneously to their releasing positions.

5. In a machine gun mounting, the combination with a rotatable training member 115 and an elevating member upon which the gun is mounted and which is pivoted to said training member, of two sets of locking devices one for locking the training member and the other for locking the ele- 120

vating member, a single hand operated control member on the elevating member, a wire operated by the said control member and means whereby the operation of the 5 said wire by the control member causes both sets of locking devices to be moved to their releasing positions.

6. In a machine gun mounting, the combination with a rotatable training member 10 and an elevating member upon which the gun is mounted and which is pivoted to said training member, of two sets of locking devices one for locking the training member and the other for locking the elevating 15 member, a single hand operated control member on the elevating member, a wire operated by said control member and means whereby the operation of the said wire by the control member causes both sets of locking devices to be moved simultaneously to 20 their releasing positions.

7. In a machine gun mounting, the combination with a rotatable training member and an elevating member upon which the 25 gun is mounted and which is pivoted to said training member, of two sets of locking devices one for locking the training member and the other for locking the elevating member, a single hand operated control 30 member on the elevating member, a wire operated by the said control member and means whereby the operation of the said wire by the control member causes said sets of locking devices to be moved in succession 35 to their releasing positions.

8. In a machine gun mounting, the combination with a rotatable training member and an elevating member upon which the gun is mounted and which is pivoted to 40 said training member, of two sets of locking devices one for locking the training member and the other for locking the elevating member, a single hand operated control member on the elevating member, a 45 wire operated by said control member and means whereby the operation of the said wire by the control member causes said sets of locking devices to be moved in succession to their releasing positions. the locking device 50 for the training member being moved to its releasing position, before the locking device for the elevating member is so moved.

9. In a machine gun mounting, the combination with a rotatable training ring and 55 an elevating arm upon which the gun is mounted and which is pivoted to said training ring, of two sets of locking devices one for locking the training ring and the other for locking the elevating arm, a single hand 60 operated control member and means whereby the operation of the last mentioned member causes both sets of locking devices to be moved to their releasing positions.

10. In a machine gun mounting, the combination with a rotatable training member 65

and an elevating member upon which the gun is mounted and which is pivoted to said training member, of two sets of locking devices one for locking the training member and the other for locking the elevating member, 70 a single hand operated control member, means whereby the operation of the last mentioned member causes both sets of locking devices to be moved to their releasing positions and anti-friction elements between 75 said training member and the part by which it is supported.

11. In a machine gun mounting, the combination with a rotatable training member and an elevating member upon which the 80 gun is mounted and which is pivoted to said training member, of two sets of locking devices one for locking the training member and the other for locking the elevating member, a single hand operated control 85 member, means whereby the operation of the last mentioned member causes both sets of locking devices to be moved to their releasing positions, and rollers interposed between said training member and the part by 90 which it is supported.

12. In a machine gun mounting, the combination with a rotatable training member and an elevating member upon which the gun is mounted and which is pivoted to said 95 training member, of two sets of locking devices one for locking the training member and the other for locking the elevating member, a single hand operated control member, means whereby the operation of the 100 last mentioned member causes both sets of locking devices to be moved to their releasing positions, and two sets of rollers interposed between said training member and a stationary part, the rollers in one set rotating about horizontal axes and the rollers in 105 the other set rotating about vertical axes.

13. In a machine gun mounting, the combination with the elements claimed in claim 1 of an elastic member having its extremities 110 fixed relative to the rotatable training member, and being engaged at some portion of its length by a member fixed relative to said elevating member, thereby producing a moment in the vertical plane due to the 115 tension in the said elastic member which is substantially equal and opposite to the turning moment in the vertical plane due to the weight of the elevating member and the parts carried thereby. 120

14. In a machine gun mounting, the combination with the elements claimed in claim 1, of a central socket on the elevating member, a carrier secured to the socket, a trunnion passing through said carrier, means for 125 connecting two guns to the said trunnion so that the guns can traverse about separate axes, the said trunnion serving for the elevation of the two guns simultaneously, and means for connecting said guns together so 130

that they can be traversed simultaneously about their separate axes.

15. In a machine gun mounting, the combination with the elements claimed in claim 1, of a central socket on the elevating member, a carrier secured to the socket, a trunnion passing through said carrier, means for connecting two guns to said trunnion so that the guns can traverse about separate axes, 10 the said trunnion serving for the elevation of the two guns simultaneously, and a detachable device for connecting said guns together so that they can be traversed simultaneously about their separate axes and one 15 of them disconnected from the other when required.

16. In a machine gun mounting, the combination with the elements claimed in claim 1, of a socket on the elevating member and 20 means for connecting a gun thereto in such a manner as to be capable of traversing and elevating movements.

17. In a machine gun mounting, the combination with the elements claimed in claim 1, of two sockets on the elevating member, 25 means for connecting a gun to each of said sockets in such a manner as to be capable of traversing and elevating movements and means for connecting said guns together so that they can be traversed simultaneously 30 about separate axes.

18. In a machine gun mounting, the combination with the elements claimed in claim 1, of two sockets on the elevating member, 35 means for connecting a gun to each of said sockets in such a manner as to be capable of traversing and elevating movements, and a detachable device for connecting said guns together so that they can be traversed simultaneously about separate axes and one of 40 them disconnected from the other when required.

In testimony whereof I affix my signature.

FREDERICK WILLIAM SCARFE.
